COÖRDINATING ACTUATING MEANS FOR MAGNETOS AND IGNITERS OF INTERNAL-COMBUSTION ENGINES.

1,155,500.

Specification of Letters Patent.

Patented Oct. 5, 1915.

Application filed October 27, 1913. Serial No. 797,617.

To all whom it may concern:

Be it known that I, THEODORE C. MENGES, a citizen of the United States of America, and a resident of Waterloo, Blackhawk county, Iowa, have invented certain new and useful Improvements in Coördinating Actuating Means for Magnetos and Igniters of Internal-Combustion Engines, of which the following is a specification.

10 My invention relates to improvements in internal-combustion engines, and it is my object in my improvement to coördinate the actions of the igniter and the magneto-electric machine in coöperation therewith, to cause them to be simultaneously actuated to obtain the best results in ignition.

This object I have accomplished by the mechanism which is hereinafter described and claimed, and which is illustrated in the 20 accompanying drawings, in which:

Figure 1 is a side elevation of an internal-combustion engine equipped with my improved coördinating actuating means for the igniter and the magneto. Fig. 2 is an enlarged plan view of the igniter with coöperating actuating parts, parts being broken away and other parts being shown in horizontal section. Fig. 3 is an enlarged detail side elevation of the parts shown in said 30 Fig. 2, with parts broken away.

Similar numerals of reference denote corresponding parts throughout the several views.

Referring first to said Fig. 1, an internal-combustion engine-cylinder 25 is supported on an engine-base 31 to project to one end thereof. Said engine in the usual way rotates a crank-shaft 29 having thereon a fixed pinion 30 in mesh with a larger gear-wheel 27 on a fixed stub-shaft 28. Integral with or fixedly connected to said wheel 27 by a common hub rotatable on said shaft 28, is a cam-wheel 32 operatively contacting a cam-roller 26, both said latter parts 32 and 26 40 being indicated only by dotted lines, and the said roller being pivoted on the right-hand end of a reciprocating horizontal bar 19 slidingly seated in spaced guide-brackets on said cylinder and its base.

50 The numeral 24 denotes a magneto-electrical machine mounted upon said cylinder and having its operating shaft 23 provided with an adjustable rack-segment 22 on its outer end.

Referring to said Figs. 2 and 3, the cylinder combustion-chamber wall 4 has an opening 20 covered by a plate 5 having two orifices through which extend respectively a fixed electrode 1 and a movable or rock-electrode 3, the latter having on its end within 55 the combustion-chamber a pin 2 adapted to rock therewith into electrical contact with the fixed contact 1. The outer end of the fixed contact is placed in electrical circuit with said magneto 24 by means of a conductor 8 leading from the magneto to a binding-post 7 on a conducting-arm 6 fixed on said fixed contact outside the combustion-chamber. On the outwardly-projecting part 12 of said movable contact is journaled a rigidly-connected rack-segment 11 and trip-finger 10, the rack-segment being meshed with the other rack-segment 22. Adjustably secured on the part 12 is a body having 60 spaced members 9, said members being adjustably connected by means of a screw 21, to permit the body to be adjusted on said part 12 to vary the tension of the spring 13 and the length of time of contact between the electrodes 1 and 2. Said body has an integral projection, and the trip-finger has an overhanging part which moves therewith, and is limited in its movement to the right by said projection. The torsion-spring 13 is 65 connected between the pin 15 on the outer end of the part 12 and the connected segment 11 and trip-finger 10 and tends to 70 yieldingly retain said trip-finger in contact with the projection on said body. A spring 75 34 is connected between the bar 19 and the lowermost member 9 to exercise yielding traction on the latter toward the right and aid the other spring 13 in moving the trip-finger 10 to the right suddenly when the latter is 80 displaced to the left and released. The 85 spring 34 being connected to the bar 19, it will be seen that when the end of the rock-arm 17 has pushed over the trip-finger to the left and releases it when riding up over the pin 16, the bar 19 is still advancing to the 90 left placing the spring 34 under an increasing tension which causes it to exercise a 95 stronger pull upon the member 9. A tension-spring 33 is yieldingly-connected between the bar 19 and the engine base, and 100 thus acts to retain the roller 26 in operative contact with the cam-wheel 32. 105

The rock-arm 17 is pivoted on the bar 19

at 18, and rides upon a pin 16 to rock upwardly as the bar 19 moves to the left, and a spring 35 retains the arm in operative contact with said pin 16. As the cam-wheel 5 acts to shift the bar 19 to the left and thus rocks up the arm 17, the end of the latter which is engaged with the trip-finger 10 rocks the latter away from the projection on said fixed body 9 to the left against the 10 tensions combined of both springs 13 and 34 and in moving to the left the trip-finger draws in the same direction the movable contact part 12 and the rack-segment 11, both moving relatively slowly until the contact 15 is established between said fixed and movable electrodes. The arm 17 continues to move to the left and rock upwardly until its end slips off from said trip-finger. The combined tensions of the said springs now 20 act to return said trip-finger to the right to strike said projecting-body 9 and break contact of the electrodes, it being understood that the reaction of the springs produces a very rapid return of the parts to 25 suddenly and rapidly shift or rock back the rack-segment 11 which acts likewise upon the other rack-segment 22 to actuate the magneto suddenly to generate a sudden high-tension current at the time that the 30 contact between the electrodes is broken, to obtain a strong igniting-spark therebetween. At other times the slow motion of the parts acts upon the magneto to produce only a negligible current, therefore my said device 35 is adapted to create a strong and instantaneous current at the exact time of ignition. The cam-wheel permits the return of the bar 19 to the right under the tension of the spring 33 when the bar has arrived at its 40 limit of movement to the left, and the end of the rock-arm 17 rocks down until it drops down past the trip-finger, with which it contacts on its return thrust to the left as before.

45 Having described my invention, what I claim as new, and desire to secure by Letters Patent, is:

1. In an internal-combustion engine, a fixed and a movable electrode, said electrodes being in electrical circuit with a magneto-electric machine, a trip-finger journaled on said movable electrode, an abutment secured on said movable electrode, said abutment being interposed in the path of movement of said trip-finger, a yieldable torsion-spring coiled about said movable electrode, connected to the outer end and also connected to said trip-finger to yieldingly draw it into contact with said abutment, 50 operative connections between said trip-finger and the driving-shaft of said magneto-electric machine, a yieldable resilient

means connected to said abutment and adapted to rock said movable electrode away from said fixed electrode, means for increasing the tension of the latter resilient means while said trip-finger and movable electrode are being rocked toward said fixed electrode, and means for actuating said magneto-electric machine suddenly and rapidly while the 65 contact is being broken between said electrodes, comprising means for pushing over said trip-finger to rock said movable electrode in to contact with the fixed electrode and then suddenly release them to permit 70 said resilient means to react to break contact between the electrodes while in so returning the operative connections with said magneto-electric machine rapidly actuate the latter to create a high-tension current in said 75 circuit.

2. In an internal-combustion engine, a fixed and a movable electrode, said electrodes being in electrical circuit with a magneto-electric machine, a fixedly-connected 80 trip-finger and a rack-segment journaled on said movable electrode outside the engine, a rack-segment on the driving-shaft of the magneto-electric machine in mesh with the first-mentioned rack-segment, a torsion-spring coiled about the outer part of said movable electrode, connected at one end thereto and at the other end to said fixedly-connected rack-segment and trip-finger, and adapted to draw said trip-finger away from 85 said fixed electrode, an adjustable body secured on said movable electrode and having oppositely-directed parts, of which one part is interposed in the path of movement of said trip-finger away from the fixed electrode, a reciprocatory-bar, a tension-spring connected between the other part of said body and said bar and adapted to draw upon said body to yieldingly rock the movable electrode away from said fixed electrode, and to be placed under an increased tension as said reciprocatory bar is moving 90 in one direction to increase the tension upon said movable electrode, and a rock-arm pivoted on said reciprocatory bar having its 95 free end adapted to move therewith and rock suitably to first engage and rock over said trip-finger to rock the movable electrode into contact with the fixed electrode, then suddenly release said finger to permit 100 the said springs to react to break the contact, said springs being adapted to rapidly return the movable parts to first position.

Signed at Waterloo, Iowa, this 14th day of Oct. 1913.

THEODORE C. MENGES.
